(57) **CLAIM**

The ornamental design for a wide jaw toenail clipper, shown and described.

DESCRIPTION

FIG. 1 is a front, side perspective view of my new design; FIG. 2 is a side elevation view thereof;

FIG. 3 is a side elevation view from the opposite side thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 is a front, side perspective view in an opened condition; with the exception of the clipper blades, the opposite front, side perspective view is a mirror image thereof.
